(57) **CLAIM**

We claim the ornamental design for a laser scanning device, as shown and described.

DESCRIPTION

FIG. 1 is a front perspective view of a first embodiment of a laser scanning device in accordance with the present invention;

FIG. 2 is a front view thereof;

FIG. 3 is a rear view thereof;

FIG. 4 is a first side view thereof;

FIG. 5 is an opposite side view thereof;

FIG. 6 is a top view thereof;

FIG. 7 is a bottom view thereof;

FIG. 8 is a side perspective view thereof;

FIG. 9 is a front perspective view of a second embodiment of the laser scanning device;

FIG. 10 is a front view thereof;

FIG. 11 is a rear view thereof;

FIG. 12 is a first side view thereof;

FIG. 13 is an opposite side view thereof;

FIG. 14 is a top view thereof;

FIG. 15 is a bottom view thereof; and,

FIG. 16 is a side perspective view thereof.

The broken lines shown in FIGS. 1, 2, 4-10, 12-16 are for illustrative purposes only and form no part of the claimed design.

The portions of FIGS. 9-16 having a lower density of stippling are a gray color, such as Pantone Cool Gray 6C.

The portions of FIGS. 9-16 having a higher density of stippling are a blue color, such as Pantone 7700C.
